HAND STAMP

Sanford E. Richeson, New York, N. Y.

Application July 24, 1936, Serial No. 92,365

2 Claims. (Cl. 101—111)

This invention relates to hand stamps and particularly to devices for protecting checks, drafts and negotiable instruments against fraudulently altering the amounts shown thereon.

Ordinary check protecting devices are of a rather complicated construction, employing intricate and expensive mechanisms, which require time and some measure of skill in their application. It is my purpose to eliminate in this invention the necessity for an operator to be skilled in the handling of such a device.

One object of my invention is to provide a novel hand stamp for printing various numbers and symbols, such as sums of money on checks or other negotiable instruments, or for printing other desirable information, such as dates.

Another object of my invention is to print the numbers and symbols in such a manner that the erasure of same becomes extremely difficult. For this purpose I provide my hand stamp with a manually operable perforating device, wherewith to penetrate the freshly printed symbols, carrying a certain amount of the still wet ink into the body of the paper, thereby making alterations of the printed letters and symbols still more difficult.

Another object of my invention is to provide a convenient hollow base for my device, the base having inside an ink pad, the printing end of the stamp being held above the pad by springs, the resistance of which can be easily overcome by applying pressure on the stamp, thereby inking the exposed characters.

Another object of my invention is to provide means for adjusting the characters without touching them by fingers, so as to prevent ink stains on the fingers.

Other objects not here enumerated will be referred to in the accompanying specification and in the claims, also in the drawing in which—

Fig. 1 is a partly sectional front elevation of my hand stamp with check protector.

Fig. 2 is a sectional side view taken on the line 2—2 of Fig. 1.

Fig. 3 is a partly sectional rear view of the same.

Fig. 4 is a view of a row of characters arranged in line as seen at the bottom part of the device.

Fig. 5 is a front view of a portion of the housing plate.

Fig. 6 is a side view of the same.

Fig. 7 is a detail view of a modified belt for the characters.

My hand stamp consists of a housing or casing 1 and a housing plate 2, both of which can be

cast, molded or stamped of sheet metal. The plate 2 has channel-shaped grooves 4 formed at its lower corners, these grooves engaging a flange 5 on the bottom of the narrow side of the casting 1. Plate 2 is made to fit into a recess 3 in the rear edge of the housing 1.

The housing holds a printing mechanism. The latter comprises a lower belt shaft 7, an upper belt shaft 8, and a control shaft 9. All these shafts are supported in respective brackets 10, 11 and 12. These brackets may be formed by stamping them out integrally with the plate 2 and bending at right angles thereto.

Both belt shafts 5 and 6 are provided with a series of independently rotatable pinions 13. Each set of two pinions located opposite each other on both shafts, carry an endless character belt 14, which is provided with printing blocks 15. The front faces of most of these blocks are shown as squares having lines or serrations, surrounding sunken or carved-out symbols 17, located preferably in the center of each square, as shown in Fig. 4. The blocks therefore print squares with white central symbols.

The serrations on the blocks 15, printing cross-hatched squares, on the face of checks, for instance, render erasures or alterations very difficult, and such erasures or alterations can be easily detected.

The printing blocks 15 are joined together to form an endless belt 14, either by casting the latter in one piece, as of rubber, for instance, as shown in Fig. 2, or they may be made of metal and fastened individually to chain links 18, these links being hinged together to form an endless chain belt, as shown in part in Fig. 7.

The rear portion of the printing block 15 has an extension in the shape of a tooth 19, adapted to enter corresponding tooth spaces in the pinions 13. The pinions are made wider than the belts and they extend to one side, so that the free portions of the pinions can engage adjustment gears or discs 20. The latter can turn on a shaft 9 and are provided with side drums or cylinders 21, on the periphery of which are printed numerals or symbols corresponding to the numerals or symbols on the belts. These drums serve therefore as indicators for setting the desired symbols in the printing position at the end of the stamp. For this purpose the front wall of the housing has slots or windows 23 through which one symbol at a time can be seen, corresponding to the symbol on the belt located at the bottom of the device and ready for printing. Longitudinal slots 22 are also provided in

the front wall for portions of the adjusting gears 20, so that they can be manually turned. With this arrangement the desired sequence of numbers or symbols can be quickly and easily set 5 into the printing position, another advantage being that the fingers do not come in contact with the printing characters, and it is easier to read directly printed symbols on the drums than their inked counterpart on the belts.

10 The adjusting or setting arrangement described is especially desirable in certain types of hand stamps where a quick and efficient change is desired or where frequent changes are necessary.

15 The mechanism described thus affords a simple and effective means for quickly adjusting the character belts and placing their symbols in any combination desired. Since the leverage is greater than that of other known constructions, the characters will move further on a turn than 20 those of ordinary types of hand stamps in which the adjusting discs are mounted directly on the upper belt shaft.

25 The perforating device, as shown in combination with the stamp, is located at the rear or outer surface of the housing plate 2 and comprises a perforating lever or member 25 fastened to the handle portion of the housing plate 2 and to the housing 1 by screws 26. The latter are held and tightened by nuts 27 placed in recesses 28. The 30 lower and wider portion of the perforating member 25 has on its inner surface, pressed or stamped out therefrom, a number of sharp projections or triangular teeth 29, which correspond to an equal number of sharp projections 30, substantially of 35 the same shape, protruding from the outer surface of the housing plate 2.

30 The pointed projections 29, 30, are shown enlarged in Fig. 3 for the sake of clearness. It is understood, however, that these projections can 40 be made smaller and proportionate to the sizes of the printed letters which these points are made to perforate.

45 It will be seen that the perforating device will cut numerous holes from both sides into the previously inked paper. By perforating freshly inked paper, a certain amount of this ink will be forced into the body of the paper, so that any subsequent alterations or erasures will be very difficult, and if made, will be easily detected.

50 The hand stamp when not in use is placed in

a supporting hollow base 31. An ink pad of an ordinary construction 32 is placed at the bottom of the base. Vertical springs 33 hold the stamp in the base at a certain height above the pad. This arrangement provides a convenient supporting means for the stamping device and also protects the surface of the pad from dust. The pad is always ready for use, and the selected characters at the bottom of the stamp can be quickly and uniformly inked by merely pressing on top of the stamp thereby forcing it down against the tension of the springs 33, until the characters touch the pad. The stamp may be then withdrawn for printing on checks or other paper which it is desired to protect.

15 My stamp has an advantage that it can be used by any one, as no special skill or training is required for its operation. Its construction is very simple, its cost being correspondingly low, so that my device can be afforded by any one who is in 20 a position to write checks or similar commercial paper.

25 It is understood, of course, that my hand stamp can be modified in its practical embodiments within the scope of my invention as set forth in 25 the appended claims.

I claim as my invention:

1. A hand stamp comprising a plate, lugs extending from the side edges of the plate at right angles thereto and provided with holes in their 30 ends, shafts supported in the holes, pinions on the shafts, flexible belts on the pinions having printing characters, wheels operatively connected with the pinions and adapted to be manually turned, and a cover in the form of a housing enclosing the 35 pinions and having openings for the wheels, the cover being attached to the plate by its edges.

2. A hand stamp comprising a plate, lugs extending from the plate at right angles, shafts supported on the lugs, pinions on the shafts, flexible 40 belts with printing characters supported on the pinions, wheels for turning the pinions, a cover in the form of a housing open at one side fitted against the plate by its open side and provided with openings for the wheels, sharp points 45 punched out outwardly in the plate, and a second plate with inwardly punched out sharp points, resiliently supported on the first plate at a distance from the sharp points thereon.

SANFORD E. RICHESON. 50
